PHOTOGRAPHIC EXPOSURE METER

Alexander T. Williams, Westfield, and Paul P. Huber,
Hillside, N. J.

Application August 16, 1954, Serial No. 31,883

Term of patent 14 years

(Cl. D61—1)

To all whom it may concern:

Be it known that we, Alexander T. Williams and Paul P. Huber, citizens of the United States of America, respectively residing at Westfield, county of Union, and State of New Jersey, and Hillside, county of Union, and State of New Jersey, have invented a new, original, and ornamental Design for a Photographic Exposure Meter, of which the following is a specification, reference being had to the accompanying drawing, forming part hereof and wherein:

Figure 1 is a front elevational view of a photographic exposure meter showing our new design;

Figure 2 is a side elevational view thereof; and

Figure 3 is a rear elevational view thereof.
The dominant features of our design reside in the portions shown in full lines.

We claim:

The ornamental design for a photographic exposure meter, substantially as shown and described.
